(57) **CLAIM**

The ornamental design for a computer numerical control CNC machine tool, as shown and described.

DESCRIPTION

1. Computer numerical control CNC machine tool

1.1: Front

1.2: Left

1.3: Right

1.4: Back

1.5: Top

The black curved cord feature that extends outwards from the computer numerical control CNC machine tool, and only present in Fig. 1.5 depicts environment that forms no part of the claimed design.
